UPHOLSTERY COVERING ATTACHING
MEANSWilliam A. Clark and Vito Asaro, Detroit, Mich.,
assignors to L. A. Young Spring & Wire Corporation, Detroit, Mich.

Application September 1, 1948, Serial No. 47,234

9 Claims. (Cl. 155—184)

1

This invention relates to a device for attaching upholstery coverings to spring assemblies and the like.

The main objects of this invention are:

First, to provide a device for attaching upholstery coverings to spring assemblies and the like which may be attached to the skirt of the upholstery covering to constitute a part thereof and readily and quickly engaged with the base frame of a spring assembly to attach and retain the upholstery without wrinkling and to distribute the retaining stresses throughout the entire edge of the upholstery.

Second, to provide a device for attaching upholstery which may be very economically produced and at the same time is capable of sustaining relatively heavy stresses and may be economically applied to the upholstery.

Third, to provide a device having these advantages which is adaptable for a wide range of uses.

Objects relating to details and economies of the invention will appear from the description to follow. The invention is pointed out in the claims.

A preferred embodiment of the invention is illustrated in the accompanying drawing, in which:

Fig. 1 is an inverted perspective view of a cushion spring assembly provided with an upholstery covering having the attaching device of our present invention applied thereto.

Fig. 2 is an enlarged fragmentary view in section on a line corresponding to line 2—2 of Fig. 1.

Fig. 3 is an enlarged perspective view of one of the attaching hooks.

Fig. 4 is a fragmentary sectional view corresponding to that of Fig. 2 illustrating a device of our invention engaged with a flat base member as distinguished from the round or rod base member shown in Figs. 1 and 2.

In Fig. 1 of the accompanying drawing we illustrate a spring cushion structure comprising a plurality of pocketed body springs 1, a base comprising a border frame 2 and longitudinal and transverse wires 3 and 4 arranged in spaced parallel relation to the corresponding members of the border frame. The upholstering, designated generally by the numeral 5, is provided with skirt or side portions 6. The details of the spring assembly form no part of our present invention.

The device of our invention, designated generally by the numeral 7, is designed to be attached to the edge of the skirt portion 6 of the upholstering. This device comprises a flexible strip 8, preferably of fabric, which is folded lon-

2

gitudinally upon itself to embrace the reinforcing or beading strand 9, there being a row of stitches 10 at the inner side of the strand, the edges of the strip extending a substantial distance to provide an attaching flap 11. This attaching flap is adapted to be stitched or otherwise secured to the edge of the upholstery, a row of stitching being shown at 12. The device is provided with a plurality of longitudinally spaced hooks 13 those illustrated being formed of pieces of light wire bent upon themselves and conformed to provide the hook bills 14. The bights 15 of the folds constituting the tips of the hooks and being downturned at 16 to facilitate engagement with a part such as the rods 3 and 4 of Fig. 1 or a flat strip 17 of Fig. 4.

The arm portions of the folded wire are conformed to provide shanks 18 terminating in bendable prongs 19 which are inserted through the fabric at the inner side of the reinforcing strand and clinched around the strand and upon the fabric covering the same as clearly shown at 20 in Fig. 2. This fixedly secures the hooks to project inwardly from the strip. The double shank prevents lateral swinging movement of the hooks and they may be readily engaged over a base part to which the upholstery is to be secured.

The strand 9 is relatively stiff but is capable of being bent as indicated at 21 in Fig. 1. The preferred form of strand comprises a wire core 22 with a paper covering or body 23 twisted about the same. This provides a strong reinforcing strand and at the same time one which can be bent or conformed as desired. The reinforcing strand provides a uniform distribution of stresses throughout the length of the attaching device even though the hooks thereof are substantially spaced. The upholstery is held against wrinkling and may be quickly applied or released. In practice the springs are compressed somewhat when the hooks are engaged. This facilitates engagement and when the pressure on the springs is released the upholstery skirt is drawn taut.

The upholstery may be applied by a relatively unskilled person and with a minimum of effort. The upholstery may be removed for cleaning or replacement by unskilled workers and this avoids the necessity of returning the cushions to the factory when the upholstery becomes worn or soiled.

We have illustrated and described our invention in a highly practical embodiment thereof. We have not attempted to illustrate the various modifications and adaptations which we contemplate as it is believed the disclosure will en-

able those skilled in the art to embody or adapt our invention as may be desired.

Having thus described our invention, what we claim as new and desire to secure by Letters Patent is:

1. A device for attaching upholstery coverings to spring assemblies and the like, comprising a strip of fabric folded longitudinally upon itself, a relatively stiff strand comprising a wire core and paper twisted therearound disposed in the bight of the folded strip, there being a row of stitches through the folded strip closely adjacent to the strand, the edges of the strip projecting beyond the stitches and constituting an attaching flap adapted to be stitched to an upholstery covering, and a plurality of longitudinally spaced hooks formed of wire folded upon itself and conformed into a hook, the bight of the wire constituting the bill of the hook, the arm portions of the wire constituting shank members, the shank members being inserted through the strip at the inner side of the strand and retainingly clinched upon the strand, said strand constituting means to facilitate uniform distribution of stresses from the hooks to the fabric strip.

2. A device of the class described comprising a strip of fabric folded upon itself, a reinforcing strand arranged in the fold of the strip, the strip being secured together at the inner side of the strand in retaining engagement with the strand, and a plurality of longitudinally spaced wire hooks provided with shanks arranged through the strip at the inner side of the strand and clampingly engaging the strand the strand being relatively stiff but bendable to permit bending of the device, the strip at the inner side of the strand providing an attaching flap which may be stitched or otherwise secured to the edge of an upholstery covering or the like, said strand constituting means to facilitate uniform distribution of stresses from the hooks to the fabric strip.

3. A device for attaching upholstery coverings to spring assemblies and the like, comprising a strip of fabric, a relatively stiff strand around which the strip is folded, there being stitches through the folded strip closely adjacent to the strand, the edges of the strip projecting beyond the stitches and constituting an attaching flap adapted for attachment to upholstery, and a plurality of longitudinally spaced hooks having bendable shanks inserted through the strip at the inner side of the strand and supported by the strand, said strand constituting means to facilitate uniform distribution of stresses from the hooks to the fabric strip.

4. A device for attaching upholstery coverings to spring assemblies and the like, comprising a strip of fabric, a relatively stiff strand around which the strip is folded, the edges of the strip projecting beyond the strand and constituting an attaching flap adapted for attachment to upholstery, and a plurality of longitudinally spaced hooks having bendable shanks inserted through the strip at the inner side of the strand and clamped about the strand, said strand constituting means to facilitate uniform distribution of stresses from the hooks to the fabric strip.

5. A device of the class described, comprising a flexible strip, a relatively stiff strand around which the strip is folded, the folds of the strip being secured together at the inner side of the

strand, and longitudinally spaced springable hooks provided with spaced shank members arranged through the strip at the inner side of the reinforcing strand and clampingly engaged with the strand whereby the hooks are supported in relatively fixed relation to the strand, the strip at the inner side of the strand constituting an attaching flap for the device, said strand constituting means to facilitate uniform distribution of stresses from the hooks to the flexible strip.

6. A device of the class described, comprising a flexible strip, a relatively stiff strand around which the strip is folded, the strip folds being secured together at the inner side of the strand to retain the strand and provide an attaching flap, and a plurality of longitudinally spaced hooks provided with shanks passed through the strip at the inner side of the strand and clampingly engaged upon the portion of the strip embracing the strand, said strand constituting means to facilitate uniform distribution of stresses from the hooks to the flexible strip.

7. A device of the class described, comprising a flexible strip, a relatively stiff strand around which the strip is folded, the strip folds being secured together at the inner side of the strand to retain the strand and provide an attaching flap, and a plurality of longitudinally spaced hooks provided with shanks passed through the strip at the inner side of the strand so that the pull thereon is sustained by the strand, said strand constituting means to facilitate uniform distribution of stresses from the hooks to the flexible strip.

8. A device of the class described, comprising a flexible strip, a strand around which the strip is folded with the edges of the strip projecting to provide an attaching flap adapted for attachment to upholstery or the like to be secured, and a plurality of longitudinally spaced hooks provided with shanks arranged through the strip at the inner side of the strand and acting to clamp the strip about the strand, said strand constituting means to facilitate uniform distribution of stresses from the hooks to the flexible strip.

9. In a device of the class described, a reinforcing stiffening strand, a flexible strip extending longitudinally of said strand and disposed around the strand to retainingly support the same and projecting to one side of the strand to provide an attaching flap for attachment to upholstery and the like, and a plurality of hooks spaced longitudinally of the strand and provided with shanks retainingly embracing said strand, said strand constituting means to facilitate uniform distribution of stresses from the hooks to the flexible strip throughout the length thereof.
